WEFT REPLENISHING LOOM

Walter H. Wakefield, Worcester, Mass., assignor
to Crompton & Knowles Loom Works, Worcester, Mass., a corporation of Massachusetts

Application May 25, 1950, Serial No. 164,173

6 Claims. (Cl. 139—231)

1

This invention relates to weft replenishing looms more particularly of the multicolor type and it is the general object of the invention to provide improved bobbin transfer revoking and magazine resetting mechanisms for such looms.

The usual multicolor weft replenishing mechanism employs a setting shaft operatively connected to a shuttle position detector and a transfrerer latch in such manner that when the shaft is moved to transfer position it moves the detector to shuttle detecting position and also lifts the transfrerer latch into the path of the lay. The shaft is returned to its normal position by engagement of the shuttle detector with the lay as the latter approaches front center on a weft replenishing beat, but this resetting occurs while the latch is still engaged with the lay during a normal transferring operation. It is for this reason that the latch cannot be positively connected to the shaft but must be connected to it by a lost motion connection. As a result the latch may not be able to drop out of the path of the lay when a bobbin transferring operation should be revoked due to misplacement of the shuttle.

It is an important object of the present invention to connect the shuttle position detector positively to the transfrerer latch so that a slight motion of the detector by a misplaced shuttle will positively move the latch out of the path of the lay. In order that the force which the misplaced shuttle must exert to revoke transfer may be reduced to a minimum, it is a further object of the invention to disconnect the setting shaft from both the shuttle detector and latch except for a very brief time when the shaft sets the magazine for transfer, after which the shaft immediately returns to its reset position in which it is disconnected from both the shuttle detector and latch.

It is a further object of the invention to provide the aforesaid setting shaft with a thrust rod or the like effective to move the shuttle position detector to its detecting position and then move away from the detector so that the latter may be moved by a misplaced shuttle without interference by the rod. The push rod is brought into action by downward movement of one or another of the vertical bobbin releasers of the magazine. The shaft becomes disengaged from the releaser as the latter approaches its normal down position and immediately returns to its reset position. Because of the fact that the shaft will be disconnected from the shuttle detector at the time of bobbin transfer revocation the shuttle need exert only enough force on the detector to move the transfrerer latch out of lay-engaging position and the shuttle detector and the revoking function is more sensitive than would be possible if the shuttle detector were also obliged to return the shaft to its normal position in addition to moving the latch.

2

Since the shuttle detector is not directly connected to the shaft some provision must be made for returning it to its normal position after a weft replenishing operation and this can be effected by a cam which comes into action to reset the shuttle feeler and latch after the latter has become disengaged from the lay due to backward movement of the latter following a replenishing operation.

In order that the invention may be clearly understood reference is made to the accompanying drawings which illustrate by way of example the embodiments of the invention and in which:

Fig. 1 is a vertical section through a weft replenishing loom transverse of the lay showing the invention applied thereto.

Fig. 2 is an enlarged front elevation looking in the direction of arrow 2, Fig. 1.

Fig. 3 is an enlarged detail plan view looking in the direction of arrow 3, Fig. 1, part of the magazine being in cross section,

Fig. 4 is a vertical section on line 4—4, Fig. 3 showing the parts in normal position preparatory to a setting operation,

Fig. 5 is a vertical section on line 5—5, Fig. 3 showing a form of friction means which can be utilized to hold the shuttle detector in its detecting position,

Fig. 6 is a view similar to the upper part of Fig. 2, but showing a releaser and the setting shaft in two different positions,

Fig. 7 shows the self-resetting mechanism for the setting shaft in two positions, and

Fig. 8 is a diagrammatic view similar to a part of Fig. 4 and illustrating the manner in which the shuttle position detector remains in its shuttle detecting position after the aforesaid thrust rod returns to its normal position incident to resetting of the setting shaft.

Referring to Figs. 1 and 2, the loom frame 1 supports top and bottom shafts 2 and 3 which are geared together so that the bottom shaft rotates once for every second rotation of the top shaft. The top shaft rotates once for each pick of the loom and causes the usual back and forth reciprocation of the lay L.

The loom is provided with a multicolor magazine M having in the present instance four vertical sliding bobbin releasers 4, 5, 6 and 7. Each releaser has a top lug 8 and a bottom lug 9 for cooperation with a color slide 10. The latter slide is mounted for horizontal sliding movement with respect to the magazine and also for angular movement. The color slide has front and back releaser lifter and depressor fingers 11 and 12, respectively, and the color slide can assume any one of four operating positions by rocking of a lever 13 which moves in time relation with some part of the loom associated with the shuttle boxes (not shown).

The rocking movements of the color slide are

controlled by a cam C secured to the bottom shaft 3 and cooperating with a lever 14 pivoted at 15 to a stand 16 secured to the loom frame. The rear part of lever 14 has a roll 17 entering a groove 18 of the cam and the cam has a decline 19, an incline 20, and a dwell 21 between the incline and decline. The cam turns in the direction of arrow a, Fig. 1.

The forward end of lever 14 is connected to an upright rod 25 the upper end of which has pivoted thereto a floating lever 26. Lever 26 has the right end thereof as viewed in Fig. 2 under a stationary pin 27 and has its left end pivoted to an upright rod 28 connected to rocking mechanism 29 operatively related to the color slide. A pin 30 is provided for the under side of the right end of lever 26 but is normally out of the path of the lever except on those beats of the loom when the weft detector (not shown) indicates weft exhaustion, whereupon pin 30 moves under the lever 26.

Each releaser slide has a dog 35 pivoted to the upper end thereof and formed with a pocket 36 to receive the lower end of a compression spring 37 the upper end of which is received by another pocket 38 at the top of the releaser. The magazine frame includes an inner plate 39 for engagement with the pocket 36, or right side of the dog as viewed in Fig. 6.

The magazine includes in its construction a transerrer arm 40 having pivoted thereto a transerrer latch 41 for engagement with a bunter 42 on the lay. A shuttle position detector 45 is secured to a detector carrier 46 rockable on a stud 47 secured as at 48 to some part of the magazine M, see Fig. 3. The detector carrier 46 is provided with an arm 49 substantially parallel to the shuttle detector 45 to which is secured a stud 50.

The matter thus far described is of common construction in multicolor weft replenishing mechanisms and operates in the usual manner. The releasers 4-7 will normally be down so that their dogs 35 will be inoperative or in the position indicated in Fig. 2 and dotted lines, Fig. 6. When the shuttle is at the magazine end of the loom, cam decline 19 causes a downward motion of rod 25 which will be idle if the weft detector fails to indicate at weft exhaustion, but if it does indicate weft exhaustion pin 30 will interrupt downward motion of the right end of lever 26, Fig. 2, whereupon rod 28 will be depressed to rock color slide 10 in a counter-clockwise direction, Fig. 2, to engage the upper lug 8 of the releaser 4 registered with it. This releaser will then rise and its dog 35, being free from the magazine plate 39, will swing out to the dot and dash line position of Fig. 6 under action of spring 37.

The shuttle is then picked to the opposite side of the loom and incline 20 will cause rod 25 to rise at some time in the cycle of the loom after the period during which lever 13 can move the color slide longitudinally. This upward movement of rod 25 causes lever 26 to rock around pin 27 as a center to rock the color slide in a clockwise direction as in Fig. 2, and if the color slide is still registered with the previously raised releaser 4 the bottom lug 9 of the latter will be depressed by the color slide and the releaser will be moved down or returned to its normal position. The cam dwell 21 holds the color slide 10 against angular motion during the rising and falling movements of the rod 25. The dwell of the color slide in its neutral position will ordinarily occur during an interval starting when

the lay has moved rearwardly after a detecting operation and will continue at least until the lay has completed its next forward motion. Downward motion of the releaser releases the bottom-most bobbin of the associated stack of bobbins and the released bobbin will move to transfer position under the arm 40.

The matter thus far described, except as noted hereinafter, operates in the usual manner to replenish a shuttle S on the lay as the latter moves forwardly by cooperation of bunter 42 and latch 41, after the latch has been set as will be described hereinafter. The replenishing operation ordinarily extends over the greater part of a two-pick cycle of the loom.

In carrying the present invention into effect the magazine M is provided with a setting shaft 55 having secured thereto a shelf member 56 adapted for engagement with the dogs of all of the releasers. An arm 57 secured to rod 55 has depending therefrom a setting member or thrust rod 58 the lower end of which is provided with a foot 59 preferably concave as at 60. Foot 59 normally overhangs the stud 50 and is preferably spaced slightly above it as shown in Fig. 4. The magazine has secured thereto a guide 61 for rod 58.

Secured to the forward end of shaft 55 is an arm 65 having a block 66 pivoted thereon and slidable in a slot 67 in arm 68 of a lever 69 pivoted on the magazine as at 70. A stop screw 71 on lever 69 engages a part 72 of the magazine to limit angular movement of the lever 69 in a clockwise direction as viewed in Fig. 7, and a second stop screw 73 limits counter-clockwise turning. A spring 74 operatively interposed between block 66 and lever 69 is normally expanded and holds the parts in the dotted line position shown in Fig. 7.

The shelf 56 is normally in the dotted line position shown in Fig. 6 and rod 58 is in its raised position. When one of the releases is moved downwardly from the dot and dash line position shown in Fig. 6 its dog engages shelf 56 and rocks the latter and setting shaft 55 to the full line position shown in Fig. 6, thereby depressing thrust rod 58 from the dotted line to the full line position, Fig. 8, and causing the shuttle position detector to move downwardly from its normal position shown in Fig. 1 to its shuttle detecting position. As the releaser approaches its lowest position its dog will be reset by plate 39 of the magazine and will move to the dotted line position, Fig. 6, out of engagement with the shelf 56.

At the time the dog moves away from the shelf 56 the arms 65 and 68 have reached the full line position shown in Fig. 7 which however is an unstable position, since the block 66 is not in line with the centers 55 and 70 but is on the same side of it as it is when the parts are in their normal dotted line position. The spring 74, having been compressed during rocking of the shelf 56 under action of the dog, is therefore free to return the parts to the dotted line position shown in Fig. 7 as soon as the dog leaves the shelf and in doing so returns the setting shaft to its normal reset position. Rod 58 rises as shaft 55 is reset so that shoe 59 will be in the raised dotted line position of Fig. 8 above the stud 50. This action of the spring 74 permits shaft 55 to set the shuttle position detector 45 for a transfer operation, but also effects immediate self-resetting of the shaft 55 to a position where the shoe 59 cannot interfere with return motion of the shuttle position detector to-

ward its normal position by a misplaced shuttle.

Extending rearwardly from the shuttle position detector carrier 46 is an arm 75 having secured thereto a stud 76 connected to the core 77 of a shielded flexible wire 78 secured to the loom by clips 79. The forward end of the core is connected as at 80 to the forward part of the latch mechanism 41 in front of the latch pivot 81 on the transerrer arm 40. The core 77 positively connects the shuttle detector 45 to the latch 41 so that these parts always move in unison.

Stud 76 extends through a vertical slot 85 formed in the top of a rod 86 the lower end of which is pivoted to an arm 87 secured to a shaft 88 rocking in the stand 16. A second arm 89 also secured to shaft 88 is positioned for periodic engagement with a cam tappet 90 formed on the cam C. Tappet 90 depresses arm 89 every second pick of the loom to cause a downward motion of rod 86.

In operation, downward motion of one or the other of the releasers 4-7 will rock shaft 55 to depress thrust rod 58 and move the shuttle position detector 45 to its shuttle detecting position simultaneously with lifting of the latch 41 to a position in the path of the lay bunter 42. As soon as the shuttle feeler and latch are thus set for a replenishing operation the dog of the descending releaser disengages the shelf 56 and the shaft 55 and rod 58 return immediately to their normal positions. The top shaft 55 is thus reset a very short time after the magazine is set for a bobbin transfer and this self-resetting is accomplished independently of the shuttle detector.

If a normal transfer follows setting of the magazine the latch 41 will be moved forwardly by the bunter and the transerrer arm 40 will insert a bobbin into the shuttle S and the shuttle detector 45 will remain down. A slot 91 in the box back 92 on the lay aligned with detector 45 permits the latter to remain down as the lay beats up to its front center position. After completion of bobbin transfer the lay moves rearwardly with the latch still engaged with the bunter and eventually the latter moves away from the latch and the latter can be returned to its normal position. During this operation the latch remains engaged with the lay for an interval of time starting before the lay reaches front center and continuing a short time after the lay moves backwardly from front center.

At a later time in the loom cycle after disengagement of the bunter and latch cam tappet 90 depresses arm 89 and as rod 86 moves downwardly its upper end engages stud 76 to rock the shuttle detector back to its normal position and cause the latch to return to its non-transfer or inoperative position by a force transmitted through the core 77. It will be noted that this resetting of the shuttle detector and latch is independent of and occurs subsequent to resetting of the shaft 55.

If the shuttle should not be correctly placed for a bobbin transfer it will lift the detector 45 as the lay moves forwardly and in doing so will cause the core 77 to exert a positive force on the latch to move the latter downwardly out of the path of the bunter 42, thereby positively effecting revocation of bobbin transfer to prevent a weft replenishing operation. This upward movement of the shuttle detector by the misplaced shuttle is possible because at the start of a revoking operation the stud 76 is at the top of the slot 85 and can move downwardly in the latter. There-

after the cam tappet 90 will effect lowering of rod 86 and if the shuttle detector has not been completely returned to its normal position by the misplaced shuttle such resetting will be effected by the tappet 90.

After the thrust rod 58 returns to its normal raised position incident to self-resetting of shaft 55 when the magazine is set for transfer the shuttle detector will be held in its down detecting position by the friction of the core 77 in the flexible wire 78. If this friction is not sufficient additional friction means may be employed including a friction pad 95 held against holder 46 by nuts 96 on the screw threaded end of stud 47, see Figs. 3 and 5.

From the foregoing it will be seen that the invention sets forth a setting shaft 55 of the self resetting type which after moving the shuttle detector to detecting position returns to normal position and is out of engagement with the shuttle detector. The latter can therefore respond to a very light force in order to effect revocation of a called transfer, such as may be exerted by the tip of a shuttle. Shaft 55 is somewhat similar to shafts previously used in multi-color weft replenishing mechanisms except that under former practice the yielding lock shown in Fig. 7 has had the stop screw 73 set to permit the lock to pass over center. In the present instance, however, the lock is not permitted to reach center position and is therefore able to effect self resetting of the shaft 55. The thrust-rod 58, after setting the magazine for a replenishing operation, returns to its normal position as indicated in dotted lines in Fig. 8, spaced above stud 50. The shuttle detector, core 77 of flexible wire 78, and the latch constitute a positively connected train which is moved in one direction by the thrust of rod 58, after which it is returned to normal position by a force which acts without being required to move shaft 55.

Having thus described the invention it will be seen that changes and modifications of the foregoing specific disclosure may be made without departing from the spirit and scope of the invention.

What is claimed as new is:

1. In a weft replenishing loom having a lay, a setting shaft, resilient lock means holding the shaft in normal position, a bobbin releaser having a motion incident to a weft replenishing operation of the loom, means operatively connecting the shaft and releaser during part of said motion of the releaser to give the shaft a setting movement and thereafter becoming disengaged from the shaft as the releaser nears the end of said motion, the lock thereupon returning the shaft to normal position, a thrust rod moving with the shaft, a train of positively connected mechanisms moving in unison including a shuttle position detector in non-detecting position and a transerrer latch out of the path of the lay when the train is in normal position, said thrust rod effective when the shaft has said setting movement thereof to move said train in one direction to move the detector to detecting position and move said latch into the path of the lay, after which the thrust rod moves away from said train as the resilient lock returns the shaft to the normal position thereof, the detector if engaged by a misplaced shuttle moving said train in the opposite direction and moving the latch out of the path of the lay while disengaged from said thrust rod, and means resetting said

train to normal position subsequent to a normal replenishing operation.

2. In a weft replenishing loom having a lay, a train of positively connected elements moving in unison and including a shuttle position detector normally in non-detecting position and a transerrer latch normally out of the path of the lay, said train causing the latch to be moved by the detector when the latter moves, cam means rotating in a two-pick cycle, reciprocable actuator means normally at rest but having a working stroke followed by an idle return stroke preparatory to a weft replenishing operation of the loom, means in said train moved by the actuator means when the latter has said working stroke only moving the train in one direction to move the detector to detecting position and move the latch into the path of the lay, the train remaining in transfer position as the actuator means has said idle return stroke, the latch being in engagement with the lay for a given interval if a replenishing operation occurs, a misplaced shuttle engaging the train after the actuator means has returned to the normal position thereof and moving the train in the opposite direction to move the latch out of the path of the lay independently of the actuator means, and resetting means acting subsequent to said interval returning said train to the normal position thereof.

3. In a weft replenishing loom having a lay, a train of positively connected elements moving in unison including a shuttle position detector normally in non-detecting position and a transerrer latch normally out of the path of the lay when the train is in the normal position thereof, a setting shaft for said train, means rocking said setting shaft in a given direction preparatory to a weft replenishing operation of the loom, return means thereafter restoring the setting shaft to the normal position thereof, means operatively connecting the train to the setting shaft when the latter moves in said given direction to move the train in a direction to move the detector to shuttle detecting position and move the latch into the path of the lay, the train remaining in the position to which it is moved by the shaft when said return means restores the shaft to the normal position thereof, the lay moving a shuttle if the latter is misplaced against the detector after said return means has restored the shaft to the normal position thereof and causing the misplaced shuttle to move said train in the opposite direction and move the latch out of the path of the lay by a force transmitted positively through said train, and means acting after a given rearward motion of the lay subsequent to a replenishing operation to return the train to the normal position thereof.

4. In a weft replenishing loom having a lay, a train of elements moving in unison including a shuttle position detector in non-detecting position and a transerrer latch out of the path of the lay when the train is in normal position, a normally stationary setting shaft, a bobbin releaser having a motion preparatory to a weft replenishing operation of the loom, a dog on said releaser operatively related to the setting shaft during part of said motion of the releaser effecting a setting movement of the shaft and becoming non-operatively related to the shaft as the releaser approaches the end of said motion, return

means thereafter immediately restoring the shaft to the normal stationary position thereof, means causing the shaft when having said setting movement to move said train to move the detector to detecting position and move said latch into the path of the lay, the train remaining in the position to which the same is moved by the shaft when the latter is restored to the normal stationary position thereof, and means acting independently of said shaft after the lay has completed a given rearward movement subsequent to a replenishing operation moving said train to the normal position thereof.

5. In a weft replenishing loom having a lay, a setting shaft, a spring lock normally holding the shaft stationary in the normal position thereof, means operative preparatory to a weft replenishing operation of the loom giving said shaft a setting movement, said spring lock immediately thereafter returning the shaft to the normal position thereof, a shuttle position detector normally in non-detecting position, a transerrer latch normally out of the path of the lay, positive connections between the detector and latch causing said detector and latch to move in unison, force transmitting means causing the shaft when having the setting movement thereof to move the detector to the detecting position thereof and cause said positive connections to move the latch into the path of the lay but ineffective to move the detector and latch when the shaft returns to the normal position thereof, the detector remaining in detecting position after the shaft has returned to the normal position thereof, and means operating subsequent to a given rearward motion of the lay after a weft replenishing operation independently of the shaft returning the detector and latch to the normal positions thereof.

6. In a weft replenishing loom having a lay, a train of positively connected elements including a shuttle position detector in non-detecting position and a transerrer latch out of the path of the lay when the train is in normal position, actuator means having a working stroke followed by an idle return stroke preparatory to a weft replenishing operation of the loom effective when having said working stroke to move the train to transfer position and move the latch into the path of the lay, the train thereupon remaining in transfer position, said train moving the latch out of the path of the lay if the detector is moved by a misplaced shuttle when the detector is in shuttle detecting position to prevent a replenishing operation, the latch being engaged with the lay for a given interval of movement of the lay incident to a replenishing operation and thereafter becoming disengaged from the lay, and means operating subsequent to said interval returning said train to normal position.
